UNITED STATES PATENT OFFICE.

JAMES H. PEARSON, OF BLOOMFIELD, INDIANA, ASSIGNOR OF ONE-THIRD TO JAMES HASLER AND ONE-THIRD TO CHARLES E. FULLER, BOTH OF BLOOMFIELD, INDIANA.

AIRSHIP.

1,255,042.

Specification of Letters Patent. Patented Jan. 29, 1918.

Application filed October 6, 1917. Serial No. 195,150.

To all whom it may concern:

Be it known that I, JAMES H. PEARSON, a citizen of the United States, residing at Bloomfield, in the county of Greene and 5 State of Indiana, have invented a new and useful Airship, of which the following is a specification.

This invention relates to airships of the heavier than air type, one of the objects of 10 the invention being to provide an airship the main body of which constitutes a sustaining plane and serves partly to house opposed propellers which are so arranged as to exert a thrust longitudinally of the 15 said sustaining plane or body.

A further object is to provide an airship having simple and efficient means for controlling the flight thereof, said airship including sustaining planes so arranged relative to the car of the machine as to automatically stabilize the machine while in 20 flight.

With the foregoing and other objects in view which will appear as the description 25 proceeds the invention resides in the combination and arrangement of parts and in the details of construction hereinafter described and claimed, it being understood that changes in the precise embodiment of 30 the invention herein disclosed can be made within the scope of what is claimed without departing from the spirit of the invention.

In the accompanying drawings the preferred form of the invention has been 35 shown.

In said drawings:—

Figure 1 is a side elevation of an airship embodying the present improvements. 40 Fig. 2 is a plan view thereof, a portion of the sustaining body and one of the wings being broken away.

Fig. 3 is a section on line 3—3 Fig. 1.

Referring to the figures by characters of 45 reference 1 designates the main sustaining body of the machine, the same having its upper and lower faces parallel while its end faces are also parallel but are inclined upwardly and forwardly. Parallel spars 2 are extended forwardly from the upper face of the body and additional parallel spars 3 are extended rearwardly from the lower face of the body. This sustaining body can be made up of a frame work hav-

ing a suitable fabric stretched thereover so 55 that the body will be light but durable.

An elevating plane 4 is pivotally mounted between the spars 2 and another elevating plane 5 is pivotally mounted between the spars 3. These planes may be controlled by cords 6 or the like extending therefrom into a car 7 which is fixedly attached to and arranged under the body 1. A rudder 8 is connected to the rear end of the car and is adapted to swing laterally, 65 this rudder being operated by any suitable mechanism provided for that purpose.

Extending laterally from the sides of the body 1 adjacent the rear end of the top surface thereof, are sustaining planes 9 70 which are inclined upwardly and outwardly, as shown particularly in Fig. 3, these planes being braced by rods 10 or the like extending from the center of the top of the body. By arranging the planes at 75 the angles shown, they operate automatically to stabilize the machine or maintain its lateral balance.

Arranged in each side of the body 1 at the center thereof is a segmental housing 80 11 which is concentric with a vertical shaft 12 journaled in the body and back from the side thereof. Secured to each of these shafts are blades 13 of a paddle wheel or propeller, these blades being adapted successively to 85 move outwardly from the side of the body, thus to displace air rearwardly and exert a forward impulse to the body 1. The two shafts 12 are provided with gears 14 constantly meshing with gears 15 which are 90 secured to a transverse shaft 16 located in the body 1 and under the housings 11. A sprocket 17 may be arranged upon the shaft 16 adjacent the center thereof, this sprocket receiving motion through a chain 18 from a 95 motor 19 located in the car 7.

It will be apparent that when the propelling wheels are rotated at high speed, they will displace air rearwardly and thus cause the machine to move forwardly, the ascent 100 and descent of the machine being controlled by the tilting planes 4 and 5 while the body 1 co-operates with the sustaining planes 9 to maintain the machine in flight.

Importance is attached to the fact that 105 the propellers, which rotate in horizontal planes, are located within the sustaining body 1 so that the thrust is thus along lines

intersecting the sustaining body from front to rear. Furthermore by having the shafts 12 set back from the sides of the body 1 the blades 13 of the propellers will not tend to 5 suck air back into the housings 11 but, instead, as each blade 13 emerges from its housing it will displace air outwardly and thence rearwardly, the displaced air being impelled rearwardly along the side of the 10 body 1 as the said blade returns into its housing 11. In other words it has been found in practice that the efficiency of the propeller will be much greater where the shaft 12 is set back from the sides of the 15 body than should the shaft be located in line with the sides. With the last named arrangement the tendency of the propeller blades would be to suck air into the housing 11 instead of displacing it rearwardly.

20 What is claimed is:—

1. An airship including a sustaining body, tiltable controlling planes at the front and back ends of the body, upwardly diverging sustaining planes at the sides of the body,

and paddle wheel propellers partly housed 25 within the side portions of the body and revoluble about normally vertical axes set inwardly from the sides of the body.

2. An airship including a sustaining body having upwardly and forwardly inclined 30 front and back ends, tilttable controlling planes at the front and back ends of the body, upwardly diverging sustaining planes at the sides of the body, housings within the side portions of the body, propellers mounted for rotation within the housings about normally vertical axes, the axes of the propellers being set inwardly from the sides of the body and concentric with the housings, and a car fixedly connected to and extending 35 downwardly from the body.

In testimony that I claim the foregoing as my own, I have hereto affixed my signature in the presence of two witnesses.

JAMES H. PEARSON.
